UNITED STATES PATENT OFFICE

GEORGE M. HOLLOWBACK, OF LOS ANGELES, CALIFORNIA

DENTAL DEVICE

Application filed October 19, 1927. Serial No. 227,124.

This invention relates to dental devices and particularly to a device for mixing investment material.

The invention contemplates a novel form 5 of paddle operating within a container in such a manner that the investment material is uniform in texture, there being no lumps or air bubbles after treatment thereof.

An object of the invention is to provide a 10 device for the treatment of investment material or any similar material so arranged and constructed that the investment material may be easily removed from the device, and regardless of a hardening of the investment 15 material within said device.

Other objects include a device which is simple of construction, positive in operation and generally superior in use and serviceability.

20 With the above and other objects in view, the invention consists in the novel and useful provision, formation, construction, association and relative arrangement of parts, members and features all as shown in a certain embodiment in the accompanying drawing, described generally and more particularly pointed out in the claim.

In the drawing:

Figure 1 is an elevation partly in section 30 of the improved dental device;

Fig. 2 is a plan view of the device;

Fig. 3 is a perspective view of a paddle used in practicing the invention, and

Fig. 4 is a cross sectional view on line 35 4—4 of Fig. 1.

Corresponding parts in all the figures are designated by the same reference characters.

Referring with particularity to the drawing, the improved dental device is designated as an entirety by A, of which a is a 40 paddle, b a container adapted to receive said paddle, c a casing for the container b and d means for rotating container c, all of which elements may be utilized in practicing an 45 embodiment of the invention.

The device includes a base 1 adapted to support a standard or pedestal 2, the pedestal being provided with an arm 3 which is bifurcated at one end as 4 to receive a head 50 6 of a stem 7. The head 6 and stem 7 form a

part of the paddle a. This head is formed with a peripheral groove 8 within which groove is received the bifurcated end 4, and the head is enlarged at 9 to rest on the top surface of said arm 3. A lock nut 10 is threaded to the arm 3 for engagement with the head to hold the same in a selected position relative to the arm. The paddle includes the member 11, which is carried by the stem 7 and which member is provided with a curved tongue 12, extending from a side 13 of said member and spaced from top and bottom ends 14 and 15 of said member. Said member 11 is likewise slotted at 16 to provide two extensions the ends of which are curved 60 as shown at 17 and 18 and the bottom end is likewise slotted at 19.

The container b is preferably formed of some flexible material and is cup shaped, being provided in the present instance with a 70 tapered wall and with a rim flange 20. The casing c includes a base 21 formed with an annular rim flange 22, and with an annular portion 23 adapted to surround the container b. A cap member 24 is adapted to 75 secure the rim flange 20 of said container to the annulus 23 as shown in Fig. 1. This cap is likewise provided with a central bore 25 to permit passage of the stem 7 therethrough. The casing 21 is rotatably mounted in a standard 26, which standard is secured to the base 1. This standard is formed with a central bore 27 within which is received a stud shaft 28, which stud shaft is secured to the base 21 by a suitable means. 80

The motor d is conventional in form and the shaft thereof carries a friction member 30 which bears against the inner surface of the rim flange 22 of the base. This motor is likewise anchored at 31 to the standard 26. 90 A switch 32 controls operation of the motor, a cord 33 leads from said switch to a suitable source of current supply. The operation of the device just described is as follows:

Investment material is usually mixed with 95 water and this investment material is placed within the cup or container b. It is necessary that this investment material should be of fine texture or smooth and free from all lumps, otherwise a casting made from the 100

investment material would be defective. The switch is turned so that a source of current is directed to the motor *d* and the motor shaft upon rotating will rotate the casing *c*, which in turn will rotate the container or cup *b* in the direction of the arrow shown in Fig. 4. The member 11 of the paddle is held stationary and as the container rotates relative thereto the investment material is smoothed by action of the curved edges of said member 11 and directed through the slots 16 and 19 and likewise between the edge 13 and the curved part 12. As the cup or container *b* is flexible in nature it will give slightly during this smoothing operation of the investment material. If for any reason the investment material should be left within the container or cup and become hard, such investment material may be readily broken from the cup or container due to its flexible nature and without the necessity of trying to chisel the investment material therefrom, which, of course, would be necessary if the container was not flexible.

It is obvious that various changes, modifications and variations may be made in practicing the invention in departure from the particular showing of the drawing without departing from the true spirit of the invention.

Having thus disclosed my invention, I claim and desire to secure by Letters Patent:

In a dental device adapted to mix investment material, a casing, a flexible container within said casing and in part spaced therefrom, a stationary paddle adapted to contact substantially with the entire inner surface of the flexible container and provided with slotted portions adapted to permit passage therethrough of investment material within the container when the container is rotated, and means for rotating the said casing and container.

In testimony whereof, I have signed my name to this specification.

GEORGE M. HOLLENBACK.
